Patented May 29, 1917.

UNITED STATES PATENT OFFICE.

ARTHUR B. COOLING, OF STERLING, ILLINOIS.

OPERATING MECHANISM FOR WASHING-MACHINES.

1,227,584.

Specification of Letters Patent.

Patented May 29, 1917.

Application filed September 25, 1914. Serial No. 863,449.

To all whom it may concern:

Be it known that I, ARTHUR B. COOLING, a citizen of the United States, residing at Sterling, in the county of Whiteside and 5 State of Illinois, have invented certain new and useful Improvements in Operating Mechanism for Washing-Machines, of which the following is a specification.

My invention has reference to mechanism 10 for washing machines, and pertains more specially to that class of said machines wherein a tub is centrally located and given a reciprocating movement upon its axis. This movement results in an abrupt stop at 15 the end of each stroke which is imparted with considerable severity to the operating devices, tending to cause an injury thereto. The purpose of the present invention is to overcome the jar consequent upon the reciprocating movement by means of novel devices whereby the shock is absorbed or neutralized at each end of the stroke.

In the drawings: Figure 1 is a plan-view of a machine equipped with my device. Fig. 25 2 is a cross-section on the line *x*—*x* of Fig. 1. Fig. 3 is a detail of the yoke and sleeve mechanism. Fig. 4 is an enlarged detail, in section, of the shock-absorbing devices. Fig. 30 5 is an enlarged detail perspective view of the tub-supporting arms in connection with their supporting elements.

1 represents a portion of a washing machine frame, in which is fixed a cross-frame 2, mounted in which is a hub 3, pivotally 35 supported by which is base plate *a* having rigidly secured thereto, a plurality of tub-supporting arms 4 that are yieldingly retained in radial relation to the spindle *d* of said base plate *a* by coil springs 5 that are 40 connected as at *e* to the outer ends of said arms 4 and as at *f* to a spider *g* which is loosely carried by said spindle and limited in its rotative action by the engagement of a lug *h* thereon with lugs as at *i* formed on 45 the hub 3. Secured to one of the arms 4 is a support 6, to the outer end of which is pivotally connected one end of a frame 7, the opposite end of said frame being supported by a plate 8, pivoted thereto, and pivotally 50 supported at its opposite end to the frame 1, as at *a*. Midway its ends the plate 8 is slidably supported on a bar 9, mounted in the frame of the machine.

Supported in the frame 7, so as to be lon-

gitudinally slidable therein, is a U-shaped 55 boxing 10, fixed to the end bar of which is a pin 11, extending rearwardly through an opening in the end bar 12 of the frame 7. Between the member 10 and bar 12 is an extensible coiled spring 13, and a similar 60 spring 14 is interposed between the bar 12 and a washer 15, held on the end of the pin 11 by means of a nut 16.

At one side of the frame 1 is journaled a main drive shaft 17, provided at one end 65 with a pulley 18, to which the power may be applied. Fixed on the shaft 17 is a gear pinion 19, engaging a gear-wheel 20, fixed on a shaft 21, rotatably mounted in the frame. On the inner end of the shaft 21 is 70 loosely mounted a sleeve 22, on the outer end of which is a crank-wheel 23, to which is connected one end of a pitman 24, the other end thereof being pivoted to a swivel-block 25, pivotally connected with the slide-piece 75 10, so as to swing in a horizontal plane. Fixed in the shaft 21 is a pin 26 adapted to engage a pair of recesses 27 in the sleeve 22, and encircling said sleeve is a yoke 28, having at one end a projection 29 pivoted to a 80 support 30 depending from the frame 2, and at the opposite end an arm 31 connected by means of a rod 32 with one end of a hand-lever 33, pivoted in the frame of the machine, as at *b*. The yoke 28 is provided in- 85 teriorly with lugs 34 which engage an annular recess 35 in the sleeve 22. By the operation of the hand-lever 33 said sleeve is moved upon the shaft 21 until it is engaged by the pin 26, whereupon the movement of 90 the shaft is imparted to said sleeve, causing the rotation thereof, and a consequent reciprocating movement of the pitman 24. This movement is thereupon first communicated to the member 10, and then to the frame 7, 95 causing a partial rotation of the arms 4 upon their axis. Upon the return movement of the pitman a similar operation of the arms is produced, in a contrary direction.

The action of the springs 5 in gradually 100 retarding the momentum of the load supported on the arms 4, is well known, but at the end of each movement of the tub devices there is a brief period of inaction, or rest, against which the pitman has to operate, in 105 beginning the movement in the reverse direction. For instance, if the pitman 24 were connected directly with the arms 6 at the

commencement of each stroke such pitman would be acting against the dead weight of the tub and load, the strain thereof being imparted rearwardly through such pitman 5 to the gearing by which it is operated, with probable injurious results thereto. By providing the springs 13 and 14 and appurtenant mechanism at the reciprocating end of the pitman such pitman is permitted to operate 10 at the beginning of each stroke independently of the tub devices, the boxing 10 being permitted a slight movement in each direction before it acts upon the frame 7 and arms 4, through the arm 6. The springs 15 5 not only have a shock-absorbing effect, but they also provide stored-power means for aiding in the return movement of the arms 4 and load mounted thereon, at each end of the stroke, or reciprocating movement of 20 such arms. The action of the springs 5 is coincident with that of the springs 13 and 14, so that when the movement of the pitman 24 begins to be imparted to the arm 6, the arms 4 are already well started on their 25 return movement. All shock or jar between the tub devices and the operating mechanism is thereby eliminated.

The action of the springs 13 and 14 is also employed in the opposite direction, to prevent 30 the action of the gearing from being too suddenly imparted to the tub mechanism.

What I claim as my invention, and desire to secure by Letters Patent of the United States, is:

A device of the class described, comprising 35 a main frame; operative mechanism mounted therein so as to oscillate; a U-shaped frame supported from said first-named frame so as to be capable of oscillation, and pivotally connected with said operative mechanism; a block slidable in said U-shaped frame; a pin secured to said block and projected through the end of said frame; a compression spring on said pin, between said frame and block, to yieldingly 40 resist the movement of said parts toward each other; a compression spring on said pin outside of said frame to yieldingly resist the movement of said block and frame away from each other; a drive-shaft mounted in 50 said main frame and provided at one of its ends with a crank-head; and a pitman connected at one of its ends with said crank-head, and at the opposite end swivelly connected with said slide-block. 55

In testimony whereof I affix my signature in presence of two witnesses.

ARTHUR B. COOLING.
